his attorney.

UNITED STATES PATENT OFFICE.

ARTHUR D. SMITH, OF VINITA, OKLAHOMA, ASSIGNOR, BY MESNE ASSIGNMENTS, TO
JOHN T. MILLIKEN, OF ST. LOUIS, MISSOURI.

MANUFACTURE OF GASOLENE.

1,239,423.

Specification of Letters Patent. Patented Sept. 4, 1917.

Application filed April 28, 1915. Serial No. 24,415.

To all whom it may concern:

Be it known that I, ARTHUR D. SMITH, a citizen of the United States, residing at Vinita, in the county of Craig, State of Oklahoma, have invented a new and useful 5 Improvement in the Manufacture of Gasolene, of which the following is a specification.

My invention relates to certain improvements in the method of destructive distillation of higher boiling point compounds of petroleum and particularly distillates known to the trade as fuel oil or gas oil, having a boiling point of 500° F. and upward.

15 A known method is to subject the aforesaid fuel oil, gas oil or distillate of a paraffin group to a temperature of 650° F. to 850° F. in a closed vessel under 4 to 5 atmospheres pressure, maintaining said pressures on vapor evolved during distillation throughout their course to and while undergoing condensation.

This method has serious drawbacks to 25 successful commercial operation due to the deposit of carbon on the heated surfaces of the inclosing vessel so that this aforesaid heated surface becomes red hot with danger of burning out the bottom of the still, the 30 deposit thereby preventing the still running to high efficiency.

My invention deals with a novel method of distillation of the above described fuel oil, gas oil or distillates of paraffin nature 35 at pressure of 125 to 150 pounds and at a temperature of 600° to 700° F., whereby so rapid a circulation is maintained during the process that the objectionable aforesaid carbon deposition on the heating surfaces of 40 the still is greatly reduced and the yield of crude gasolene increased some 70 to 80%, due to ability to prolong the process by removing danger of burning out the heated metal surfaces.

45 However highly desirable this process, it is evident from the chemical composition of the aforesaid gas oil, fuel oil or distillate, that carbon is continuously formed during the breaking down of compounds of higher 50 to those of lower molecular weight, which carbon, while prevented to a great extent in my process from adhering to the heated surfaces, must eventually bring the process to end if not removed; and my method further provides for removal of this objection-

able carbon by sweeping at intervals portions of the charge to suitable interchangeable filters and returning the carbon free fluid to the still together with fresh distillate, the action being thus rendered continuous, a most essential feature as regards increasing the output from a given size of apparatus. By carbon free fluid is meant a liquid from which suspended carbon particles likely to deposit on heated metallic surfaces have been removed.

It has been noted that, however desirable is the method of applying pressure throughout the course of distillation to and while vapors are undergoing condensation, nevertheless a certain constant loss takes place through evaporation of the lighter gasolene passing from the liquid to gaseous state as the condensate flows from the end of the condensing coil to the receiving tank 75 where it passes from high pressure to atmospheric pressure with great lowering of surface tension; and I have discovered that this aforesaid loss may be reduced from forty to fifty per cent. by keeping not only the 80 vapors themselves under pressure to and while undergoing condensation, but the liquid condensate as well, relieving pressure in excess of 150 pounds only at the storage tank. I allow the latter to nearly fill before 85 removal of contents, and I blend the same immediately with low gravity naphtha, thus entraining and fixing lighter portions of condensate produced under pressure and incorporating these compounds to a large extent a permanent part of the final crude 90 gasolene so that subsequent evaporation is reduced to a minimum. Further details of the invention appear in connection with the following description of the process and apparatus for carrying it out.

95 A suitable form of apparatus for the practice of my invention is illustrated in the accompanying drawing, which is essentially diagrammatic in character and which represents the apparatus partly in vertical longitudinal section, and partly in side elevation.

100 Referring to the drawing, the gas oil, fuel oil or paraffin residue is charged from a storage tank 10 by a pump 11, through the pipe line 12 to a boiler or still, which may be of any suitable type. The still shown in the drawing consists of the drum or shell 13 which is mounted in a suitable setting over the furnace 14 with its longitudinal 105 110

axis at a slight downward inclination from front to back. Nipples or connections 15 open into the bottom of the shell at its front and back ends and these nipples are connected to the tube boxes or headers 16 which are arranged at the front and back ends of the furnace chamber. A series of parallel tubes 17 connect the headers, and the tubes and headers are arranged at a considerable upward inclination from back to front below the boiler shell in the path of the hot gases from the furnace. The boiler outlet 18 is provided with a vacuum valve 19 and safety valve 20. A vapor line pipe 21 leads from the boiler outlet to the condenser 22. The boiler is also provided with a pressure gage 23 and a thermo-electric pyrometer 24. An outlet pipe 25 for residuum leads from the lower end of the back header 16, and is normally closed by a valve 26. Within the boiler are arranged a series of revolving brushes 27, which may be made of steel wire or other metal capable of withstanding heat and corrosion. The brushes are operatively connected together with driving chains arranged within the boiler, and the rear brush is mounted on a shaft which passes through a stuffing box in the side of the boiler and is provided with a pulley 28 on its outer end. The pulley 28 is belted to a pulley on the line shaft 29 whereby the series of brushes may be rotated at a suitable speed. The brushes are rotated in the direction shown by the arrows in the drawing; thereby assisting in maintaining the circulation in the still, and also sweeping the bottom of the boiler shell free from the carbon which has a tendency to deposit and accumulate therein during the operation of the apparatus. Preferably the drum or shell 13 has a large capacity in proportion to the capacity of the tubes. The angles of inclination of the drum, tubes and other parts of the still are not restricted to those shown in the drawing. The mechanical agitation of the liquid in the drum by the sweeping action of the brushes facilitates rapid circulation and assists in preventing deposition of carbon in the apparatus. It is understood that the arrangement of parts shown in the drawing is only a typical arrangement of one form of still, and that it can be varied according to requirements for proper circulation, type of boiler or still used, or greater or less tendency of the carbon to deposit. Any suitable arrangement of brushes may be used to assist circulation and to sweep the metal surfaces clean.

As the suspended carbon accumulates, a portion of the liquid contents of boiler is withdrawn at intervals, for instance every thirty minutes, through the residuum outlet 25 to the filter 30 where it is passed through fullers' earth, spent bone char, or product of similar nature and thereby made free from

carbon. The distillate is drawn off the bottom and returned by the pump 11 through the pipe line 12 into the boiler 13, together with such fresh distillate from the tank 10 as may be necessary to take the place of the 70 gas oil freed into the lighter hydrocarbons.

The filters 30 may be of any convenient size and number, and are provided with suitable stop cocks 31 so that those not being charged may be in process of preparation 75 when those in use become clogged with carbon and are no longer efficient. The filtering process being thus intermittent renders the process as a whole continuous.

The vapors leaving the vapor line 21 are 80 condensed in the coil 32 of the condenser 22, and fall as liquid condensate into a condensing tank 33. The same pressure is maintained in the condensing tank as throughout the remainder of the system. Any excess of 85 pressure above 150 pounds on the system is relieved by the relief valve 34. When the condensing tank is nearly full, its contents may be withdrawn through the valve 35 and mixed immediately with low gravity naphtha, thus fixing the lighter hydrocarbons which hitherto have been allowed to escape in apparatus wherein the condensate receiving tank has been kept at atmospheric pressure. 95

This invention is not restricted to the precise temperatures, pressures and times set forth above, nor to the apparatus shown and described.

Having thus described my invention, what 100 I claim as new and desire to secure by Letters Patent is:

1. The process of producing crude gasoline continuously which consists in distilling in a closed system of circulating channels 105 the liquid portions of the paraffin series having a boiling point of 500° F. or above and known familiarly as gas oil or fuel oil at a pressure from about 125 to 150 pounds and at a temperature ranging from about 600° 110 to 700° F. while maintaining rapid circulation throughout the system, and removing suspended carbon in the charge by intermittent filtration of portions of the charge, whereby filtered oil together with fresh oil 115 may be added to the charge without clogging the system.

2. The process of producing crude gasoline continuously by destructive distillation in a still or closed system subjected to heat 120 throughout which comprises effecting rapid circulation of the contents of the system in a cyclic path by a mechanical agitating device to prevent deposit of carbon therein, and collecting carbon in suspension in said 125 contents and removing said carbon from the still.

3. The process of producing gasoline continuously by destructive distillation in a closed apparatus forming a cyclic system 130

and having heating surfaces inclined underneath, which comprises preventing the deposition of carbon on said surfaces by mechanically circulating the charge over 5 said surfaces toward their lower ends, providing portions of the apparatus where the carbon particles can collect, periodically removing said carbon particles by intermittent filtration, and returning the filtrate to the 10 system for further treatment.

4. The process of producing crude gasolene continuously by cracking in a closed system of tubes and receptacles arranged for positive circulation of the charge therein, which

comprises condensing the lighter hydrocarbons as given off, and preventing clogging of the still by removing from time to time portions of the charge from the lowest point of action, filtering said portions in a suitable filter, and returning the carbon free filtrate 20 to the system together with as much additional fresh distillate as may be necessary to take the place of the distillate converted into lighter hydrocarbons.

Signed at Vinita, Okl., this 24th day of 25 April, 1915.

ARTHUR D. SMITH.
